UNITED STATES PATENT OFFICE.

AENEAS ANDREW SHAW, OF VICTORIA, BRITISH COLUMBIA, CANADA.

DEVICE FOR THE PROTECTION OF BANK-TELLERS AND BANKERS.

1,199,718.

Specification of Letters Patent. Patented Sept. 26, 1916.

Application filed January 25, 1915. Serial No. 4,391.

To all whom it may concern:

Be it known that I, AENEAS ANDREW SHAW, of the city of Victoria, in the county of Victoria, in the Province of British Columbia, Canada, gentleman, have invented a certain new and useful Device for the Protection of Bank-Tellers and Bankers; and I do hereby declare that the following is a full, clear, and exact description of the 10 same.

My invention is designed for the protection of bank tellers from attacks by persons attempting to rob banks and for the protection of bankers from losses occasioned by 15 robberies, such that by the pushing of a foot trip beneath the counter a steel sheet is released and raised by means of springs to a position immediately in front of the teller and as the said steel sheet is raised an 20 electric bell is rung to give warning.

The objects of my invention are, first, to protect the lives of those employed as tellers in banks and other places where large sums of money are being handled and which are 25 liable to be attacked by persons intending to rob, by making it impossible for them to shoot the teller; and secondly, to protect the bankers from the loss of large sums of money caused by such robberies, by making it impossible 30 for persons intending to rob to force the teller at the point of a gun to give up the money at hand; and, thirdly, to afford a facility for the police to capture such robber, the ringing of the electric bell giving 35 warning, the electrical circuit for which being completed by the raising of the aforesaid steel sheet.

In the accompanying drawings I have 40 shown how my said invention may be conveniently and advantageously carried into practice.

Figure 1, is a vertical section of the back view of the entire device when the steel sheet is raised; Fig. 2, a top view of the device as it appears after the removal of the counter top, the sheet being sectioned; Fig. 3, a sectional view of the device when the steel sheet is down; Fig. 4, a detail view in perspective of the foot trip before the steel 45 sheet is released; Fig. 5, a detail view in perspective of the foot trip when the steel sheet is released; Fig. 6, a detail view in perspective of the slide through which the leg projecting from steel sheet and the 50 spring passes.

Similar letters refer to similar parts throughout the several views.

A, is the steel sheet which is pulled down through the counter *w* by means of the rope *T* which is hooked onto the hook and plate *F* and which passes through a hole in the floor *y* through the pulleys *R* and up through a hole in the floor *y* and hooked onto the hook *M*. The rope *T* is then tightened and the steel sheet *A* pulled down by placing the dog *d* on the ratchet wheel *V* and at the same time placing the dog *d'* on the ratchet wheel *X* and operating the lever *e* to rotate the drum *b* until the steel sheet *A* is lowered so that the cap *C* is level with the top of the counter *w*. The steel sheet *A* is then kept in position (as shown in Fig. 3) by means of the foot trip (shown in Figs. 4 and 5). Fig. 4 shows the trip which is operated by moving the lever *L* backward or forward. 75 When the steel sheet *A* has been lowered as heretofore described the lever *L* is drawn back thus forcing the plate *K* on the plate *F*. The dog *d* and the dog *d'* are then released and the rope *T* slackened. 80

To release the steel sheet *A* from its position as shown in Fig. 3, and restore it to its position as in Fig. 1; the lever *L* is pushed with the foot thus drawing the plate *K* off the plate *F*, and releasing the tension 85 on the springs *E* and forcing the steel sheet quickly into its position as shown in Fig. 1; at the same time the plate *s*, which is fastened on the steel sheet *A*, strikes the push button *r*, thus connecting the electric 90 current between the battery *p* and the electric bell *n*, causing said bell to ring.

G, are steel guide plates fastened on the lower side of counter-top *w*, one on each side of steel sheet *A* for the purpose of 95 strengthening the said counter top after a slot has been made in it to allow the steel sheet *A* to be operated through it.

Four iron rods *H* extend through the floor *y* secured thereto by a nut above the 100 floor and one below, and are connected to the plate *G* by a nut above the plate *G* counter-sunk into the underside of the counter top *w* and by another nut on the lower side of the said plate *G*. 105

t, is an iron plate counter-sunk into the floor *y* and through which the springs *E* and the leg *D* passes.

There is a spring *E* at each angle of the steel sheet *A*. One end of this spring is 110

fastened by means of a hook to the plate G and the other end is fastened to the leg D at K by means of a small bolt.

C, is a brass plate fastened to the top edge of the steel sheet A and for which a recess is cut in the top of the counter w, thus when the said steel sheet A is lowered as in Fig. 3, the top of the counter w is perfectly smooth. The legs D extend 10 through the floor y when the steel sheet A is lowered.

In order that the plate K shall quickly respond to the push of the lever L, I have placed a roller P in the end of plate K.

15 The foot trip (as shown in Figs. 4 and 5) is placed beneath the counter in such a position that the lever L may be reached with the foot, and is kept in position by means of the four bolts i passing through 20 the floor y and having nuts l screwed on them below the floor y.

The drum b and attachments may be placed in any convenient place in the building and need not be near the teller's counter 25 as it is only used to lower the steel sheet A, but the pulleys R would have to be so arranged beneath the floor that the rope T would come up through the floor, immediately beneath the drum b.

30 The electric bell n may be placed on the outside of the building and may be of such

size as is deemed necessary to warn the public and the police that a robbery has been attempted. In all places where electricity is used for lighting purposes a battery will 35 not be necessary. An attachment can also be made to the police station by connecting the push button r with the ordinary police call service, to give warning.

What I claim as my invention and desire 40 to secure by Letters Patent is:—

In a protective apparatus for banks and the like, the combination of a support having an elongated slot, a plate slidably mounted in said slot, said plate having substantially parallel rods extending from one edge of said plate, guide plates for said rods, tension springs connected at one end to the support and at the other end to the outer ends of said rods, guide rods on opposite sides of said plate connected to said support, means for moving said plate in one direction against the tension of the springs to a position so that the edge of the plate is flush with the support, means for locking 55 the plate in this position and means for releasing said locking means.

Dated this 18th day of January, 1915.
AENEAS ANDREW SHAW.

Signed in the presence of:—

J. A. AIKMAN,
F. L. SHAW.
